UNITED STATES PATENT OFFICE.

ALFRED K. WANDER, OF CHICAGO, ILLINOIS.

TROUSERS APPLIANCE.

1,368,866.

Specification of Letters Patent. Patented Feb. 15, 1921.

Application filed January 17, 1920. Serial No. 352,127.

To all whom it may concern:

Be it known that I, ALFRED K. WANDER, a citizen of the United States, residing at Chicago, in the county of Cook and State 5 of Illinois, have invented certain new and useful Improvements in Trouser Appliances, of which the following is a specification.

This invention relates to an appliance 10 adapted to be attached adjacent the waistband of a pair of trousers, the purpose being to afford support therefor, to gather in the rear of the trousers any slack occurring in the waist band thereof, and to prevent 15 the shirt which lies in contact therewith from creeping upwardly. An exemplification of this invention is illustrated in the accompanying drawing wherein—

Figure 1 shows in perspective the upper 20 portion of a pair of trousers to the inner side of which the present appliance is attached;

Fig. 2 is an enlarged fragmentary view thereof in plan; and

Fig. 3 is a similar view showing a modified construction.

Any suitable flexible material such, for instance, as webbing, or elastic if desired, is selected for a strap which forms an essential part of this invention, the strap being 30 used in the form of two separate sections designated as A and B. In practice each section is by preference a counterpart of the other, but for the sake of illustrating two constructions conveniently, I have shown in 35 Figs. 1 and 2 these two sections to be differently formed. Referring particularly to these figures, one end of each strap section is provided with a hole, through which may be received a button 6 located conveniently 40 on the inner side of the trousers waist band near the center of the back thereof, a second button being also secured to the trousers on the opposite side of the back center a distance therefrom about equal to that of the 45 first button. These two buttons, denominated as 6 and 7, are adapted to be attached in the usual manner to the strap sections A and B respectively, which, as already stated, are formed with button holes for 50 this purpose. Between these buttons is a floating loop 8 on which are mounted two parallel sleeves 9 and 10, each adapted to function as a roller and to lie within a bend of the two strap sections A and B respectively, which sections proceed first from the 55 two buttons 6 and 7 toward each other, and

then take a turn around the two rollers 9 and 10, thereafter extending away in opposite directions, as shown. In all particulars that have so far been described, the two 60 strap sections may be exactly alike.

The section A is threaded through a length-adjusting appliance such as the buckle 11 which operates upon the usual friction or clamping principle, and near its 65 end which is opposite the button 6 the section A takes a turn through an eye 12 which is adapted to coöperate with the button 13 (see Fig. 1), the proximate extremity 14 of the strap being held by the buckle in any 70 desired manner.

Instead of employing this buckle and eye arrangement, it is entirely practicable to form both strap sections as shown in the construction of section B, wherein such auxiliary parts are omitted, use being made instead of one or more holes 15 near the end 16 of this section, each adapted, as required, to receive a button 17 by which means the strap is secured to the inner side of the 80 trousers waist-band. The length adjustments of this strap section are effected simply by buttoning into the desired hole 15.

The appliance, when used as indicated, provides a take-up device that is preferably, although not necessarily, formed of some elastic material. It serves to gather up at the rear of the trousers any slack remaining at the waist-line, and serves further, by reason of its close contact with the 90 shirt that is tucked inside the trousers, to keep the shirt from creeping up. Movements of the wearer are not inconvenienced, but are in fact rendered more comfortable, by the use of this device as the floating loop 95 8 acts to equalize the strain on both strap sections by transferring it from one to the other according as occasion may require, this action occurring without appreciable wear or effort due to the provision of the 100 sleeve rollers 9 and 10.

In Fig. 3 I have shown a device of similar construction which is applicable to the outer side of the waist-band of the trousers as a supporting means therefor in lieu of a 105 belt or suspenders. In this instance, use is made of an ordinary belt that is severed to provide two parts C and D each of which has suitable means (not shown) to connect with the other at the front of the trousers, 110 their ends that lie toward the rear of the trousers being each provided with a loop 18

that at all times remains spaced apart from the other, as shown. Through these loops is threaded a strap 19, preferably, although not necessarily, made of some elastic material, this strap also taking turns about two rollers 20 and 21 that are carried in the floating member 22 which normally lies close to the middle of the back, the strap ends extending oppositely to connect as to buttons 10 23 with two points remote from each other that are situated at the back of the trousers. This form of appliance is yielding in the same manner, as has been explained in connection with the device of Figs. 1 and 2, and 15 possesses all the advantages thereof except in regard to the shirt holding feature which, of course, is absent.

The devices as described and shown represent two exemplifications of this invention, 20 but may be obviously modified or altered within the limits defined by the appended claims, without sacrificing the features which are novel to this invention.

I claim:

25 1. In combination with a trousers waist band, a trousers appliance comprising two straps, each strap being flexed or looped at its inner end to provide a relatively short under section and a relatively long overlying outer section, means for securing each underlying relatively short section to the trousers waist band at a point at a substantial distance from the rear center thereof, means for securing each overlapping longer 30 section of the strap to the trousers waist band at a point located at a substantially greater distance from the center than the first mentioned point, and normally centrally disposed floating attaching means 35

slidably engaging the bends or loops in the 40 respective straps, the point of engagement being intermediate the proximate points of attachment for the respective straps, whereby freedom of movement is afforded and the floating attaching means are permitted to 45 move back and forth between the inner points of attachment, substantially as described.

2. In combination with a trousers waist band, a trousers appliance comprising two 50 elastic straps, each strap being fixed or looped at its inner end to provide a relatively short under section and a relatively long overlying outer section, means for securing each underlying relatively short 55 section to the trousers waist band at a point at a substantial distance from the rear center thereof, means for securing each overlapping longer section of the straps to the trousers waist band at a point located at a substantially greater distance from the center than the first mentioned point, and normally centrally disposed floating attaching means 60 slidably engaging the bends or loops in the respective elastic straps, the point of engagement being intermediate the proximate points of attachment for the respective straps, whereby freedom of movement is afforded and the floating attaching means are permitted to move back and forth between the inner points of attachment in conformity with the stretching and contracting 65 of the elastic straps, substantially as described.

ALFRED K. WANDER.
